UNITED STATES PATENT OFFICE.

WILLIAM R. FOX, OF GRAND RAPIDS, MICHIGAN.

TABULATOR FOR TYPE-WRITERS.

No. 880,290.

Specification of Letters Patent.

Patented Feb. 25, 1908.

Application filed June 7, 1907. Serial No. 377,751.

To all whom it may concern:

Be it known that I, WILLIAM R. FOX, a citizen of the United States, residing at the city of Grand Rapids, county of Kent, State of Michigan, have invented certain new and useful Improvements in Tabulators for Type-Writers, of which the following is a specification.

This invention relates to improvements in tabulator mechanisms for typewriters.

The objects of this invention are,—first, to simplify and increase the efficiency of such devices, and at the same time provide an effective control of the released carriage to prevent its striking the stop with a violent blow, which of necessity increases the wear and tear on the machine. Second, to provide an improved construction and arrangement of parts for actuating the stop means, whereby the same will be moved yieldingly into position. Third, to provide an improved construction and combination of parts whereby the release of the carriage is definitely controlled in relation to the other parts. Fourth, to provide an improved construction of the brake or controller means for properly retarding or controlling the carriage after it is released.

Further objects, and objects pertaining to details of construction, will definitely appear from the detailed description to follow.

I accomplish the objects of my invention by the devices and means described in the following specification.

The invention is clearly defined and pointed out in the claims.

The portions of a typewriter necessary to properly describe and understand all of the features of my invention are sufficiently illustrated in the accompanying drawing, forming a part of this specification, in which,

Figure 1 is a detail rear elevation view of portions of a typewriter with my improved tabulator means in place, parts being broken away; Fig. 2 is a side elevation view, partially in section, on line 2—2 of Fig. 1, showing the lower portion of my improved mechanism, the position of the typewriter frame being indicated merely by dotted lines; Fig. 3 is an enlarged detail transverse sectional view on line 3—3 of Fig. 1, showing the brake or controller mechanism in its relation to the driving drum of the carriage; Fig. 4 is an enlarged detail sectional view taken on a line corresponding to line 4—4 of Figs. 2 and 3; Fig. 5 is an enlarged detail

sectional view through the brake or controller mechanism, taken on a line corresponding to line 5—5 of Figs. 1, 2, 3 and 4; Fig. 6 is a detail section view on line 6—6 of Fig. 1, showing the rock shaft arm 20 and its relation to the stop bar; Fig. 7 is a detail sectional view on line 7—7 of Fig. 1, showing further details of the parts illustrated in Fig. 6; Fig. 8 is a detail sectional view on line 8—8 of Fig. 1, through the escapement device and parts there illustrated, and Fig. 9 is a detail sectional view taken on line 9—9 of Fig. 2.

In the drawing, all of the sectional views are taken looking in the direction of the little arrows at the ends of the section lines, and similar numerals of reference refer to similar parts throughout the several views.

Referring to the reference numerals of the drawing, the main frame 1, the carriage 2 with its feed rack 3 and escapement wheel and rack 4 are of the form commonly used in Fox typewriters, as clearly illustrated in my Patent No. 839,129, issued to me on the 25th day of December, 1906, for tabulator, and will not need to be more fully or particularly described here, the escapement wheel being controlled by escapement dogs 5—5 exactly similar to the escapement dogs appearing in my said patent and supported in the same way and being actuated by the usual means for actuating such escapement dogs.

The various parts of my improved tabulator mechanism are connected to and actuated by the transverse rock shaft 6. An arm 7 extends downwardly therefrom and is held normally towards the front of the machine by the coiled spring 8. A push rod 9 extends out through the toe-plate 11 of the frame and is provided with a push button 10. A stop collar 9' abuts against the inner side of the toe-plate and serves as a stop to limit the movement when pressure is released from the button 10 to permit the spring 8 to throw all of the parts to the inoperative position.

A pivot lock piece 12 with a notch 12' is arranged to engage back of the stop collar 9' to lock the mechanism and prevent its accidental operation. This is of great advantage in avoiding interference with the machine by meddlesome persons in the absence of the operator.

In the actuation of the device, the stop bar 21 with its pointed upper end 25 is arranged in suitable guides in the back part of the frame 1, and is elevated by the rock shaft

arm 20 when the rock shaft 6 is operated. The lower end of the bar 21 is bifurcated, and the bifurcated sides are turned into eyes which embrace the pivot pin 23. The rock 5 shaft arm 20 is slotted on its under side at 22 to receive this pivot pin 23, and is held normally in engagement by the bifurcated spring 24, which is secured to the under side of the rock shaft arm 20. The notched bar 10 26, carrying the tabulator stops 27, is arranged on the carriage so that the stops 27 co-act with this stop bar 21 when it is raised into position. A plurality of stops 27 is provided, so that by placing the same at different points on the bar 26, a plurality of columns can be made. Should the bar 21, when it is raised, strike one of the stops 27, the spring 24 will yield so that the remaining parts of tabulator mechanism will be allowed 15 to operate, and the stop 27 will move off from the bar 21 when the carriage is released.

A lever 17 with a beveled finger 19 acts upon the inner escapement dog 5 to release the carriage, the lever 17 being pivoted on the pivot 18 on the escapement dog rock shaft 18'. These parts act the same as those of my patent above referred to for releasing the dog. This lever 17 is connected by a rod 25 14 to a rock shaft arm 13 on the rock shaft 6. Lost motion and adjustment is provided for by screw threading the lower end of this rod 30 14, and applying lock stop nuts 15—16 on the rod each side of the said arm, which is perforated to receive the lower end of the rod. This lost motion is provided for so that 35 the stop bar 21 will be elevated before the carriage is released.

To control the carriage, there is the usual 40 spring drum 39, the opposite sides of which I make flat in order that a brake mechanism may be applied thereto. The brake mechanism is actuated by an arm 28 on the rock shaft 6, which carries a pivoted arm 29 that is provided with wedge or cam shaped projections 30—33 for acting upon the brake arms. The brake arms are supported on a 45 fixed arm or shaft 31 secured to the frame 1, the arms or members 32—33 being symmetrical and pivoted on the shaft or rod 31 and arranged to pinch or press against the 50 opposite sides of the wheel 39 so as not to disturb it upon its bearing. So that this may be accomplished without strain on the bearing of the spring drum, and so that a 55 mere retarding action will be secured, the arm 32 is provided with lugs 32' on opposite sides, which contain elongated holes 32'', which embrace the rod 31; and the arm 33 has corresponding lugs or ears 33' with 60 elongated holes 33''. The arms 32—33 are held towards each other yieldingly by a rod 34, adjustable by means of a screw 35, a coiled spring 36 being on the outer end of the rod and retained in place by the cotter pin 5 37. These brake pieces are provided with

leather or felt faces 38—38. This spring device is below the shaft 31, so that, when the cam faces 30—30 are withdrawn from between the outturned ends of the arms 32—33, it will draw the arms towards each other; and, when this cam face is completely removed, the shaft 31 will contact at the ends of the slotted or elongated holes with the ears 32'', 33'', the said arms will fulcrum thereon, and the spring will then 75 serve to release the brake and permit the spring drum and carriage to move freely.

When the cam faces are pushed up, they act on the arms, close the sides of the brake onto the spring drum, and then separate 80 them from their bearing shaft 31, so that they act equally on each side of the drum, and consequently have no tendency to lateral stress or strain on its bearing.

I have described this invention in the form 85 which I have found by experience and experiments to be very satisfactory and effective. I desire to remark, however, that the mechanism may be considerably varied in its details without departing from my invention. 90

The timing and relation and actuation of the parts from a single button, as I have shown, would be of advantage with other forms of stop, release and brake mechanism, but obviously it is especially well adapted 95 for use with the particular means I have shown.

The brake mechanism I have shown is of special advantage for the reasons that I have indicated, and I shall desire to claim 100 the same broadly in connection with any stop and release mechanism.

Having thus described my invention, what I claim as new and desire to secure by Letters Patent is:

1. In a tabulator mechanism for typewriters, the combination of the main frame 1 of the typewriter; a carriage 2 thereon; an escapement mechanism for the carriage; a stop bar 26 on said carriage with adjustable 110 stops 27 thereon; a rock shaft 6 arranged transversely through the main frame; a movable stop bar 21 with tapered point arranged in guides on the frame 1 of the typewriter in position to be moved into 115 operative relation with the stop or stops on the said carriage; a release lever or means 17 to act upon the escapement and release the carriage; an arm 13 on the rock shaft; a rod 14 connected to the lever 17 and extending 120 through a perforation in the arm 13; adjustable stops 15 and 16 on the rod 14, whereby the release mechanism is timed to operate subsequent to the elevation of the stop bar 21; a spring drum 39 for actuating 125 the carriage; a brake mechanism for engaging the opposite faces of the said spring drum, consisting of a pair of arms or members 32—33 supported on a fixed shaft 31 by the said shaft extending through slotted holes in said 130

arms; adjustable spring devices for holding the said arms normally towards each other; an arm 28 on the rock shaft 6; a pivoted arm 29 on the rock shaft arm 28 carrying wedge or cam-shaped members 30—30 to act upon the arms of the brake mechanism timed to act simultaneously with the release mechanism; a downwardly-depend ing rock shaft arm 7 on the rock shaft 6; a spring 8 for throwing the same normally forward; a push rod 9 with a button 10 at its forward end for actuating the said tabulator mechanism; a stop collar 9' on the rod 9 for limiting its movement; and a notched lock plate 12 for engaging the stop collar 9' to secure the mechanism against accidental operation, all coacting substantially as described and for the purpose specified.

2. In a tabulator mechanism for typewriters, the combination of the main frame 1 of the typewriter; a carriage 2 thereon; an escapement mechanism for the carriage; a stop bar 26 on said carriage with adjustable stops 27 thereon; a rock shaft 6 arranged transversely through the main frame; a movable stop bar 21 with tapered point arranged in guides on the frame 1 of the typewriter in position to be moved into operative relation with the stop or stops on the said carriage; a release lever or means 17 to act upon the escapement and release the carriage; an arm 13 on the rock shaft; a rod 14 connected to the lever 17 and extending through a perforation in the arm 13; adjustable stops 15 and 16 on the rod 14, whereby the release mechanism is timed to operate subsequent to the elevation of the stop bar 21; a spring drum 39 for actuating the carriage; a brake mechanism for engaging the opposite faces of the said spring drum, consisting of a pair of arms or members 32—33 supported on a fixed shaft 31 by the said shaft extending through slotted holes in said arms; adjustable spring devices for holding the said arms normally towards each other; an arm 28 on the rock shaft 6; a pivoted arm 29 on the rock shaft arm 28 carrying wedge or cam-shaped members 30—30 to act upon the arms of the brake mechanism timed to act simultaneously with the release mechanism; a downwardly-depend ing rock shaft arm 7 on the rock shaft 6; a spring for throwing the same normally forward; a push rod 9 with a button 10 at its forward end for actuating the said tabulator mechanism; and a stop means for limiting its movement, all coacting substantially as described and for the purpose specified.

3. In a tabulator mechanism for typewriters, the combination of the main frame 1 of the typewriter; a carriage 2 thereon; an escapement mechanism for the carriage; an adjustable stop means on the said carriage; a rock shaft arranged transversely through the main frame; a movable stop means

actuated from said rock shaft; a release means for the escapement; an arm on the rock shaft with connections from the release means thereto; a spring drum 39 for actuating the carriage; a brake mechanism for engaging the opposite faces of the said spring drum consisting of a pair of arms or members 32—33 supported on a fixed shaft 31 by the said shaft extending through slotted holes in said arms; adjustable spring devices for holding the said arms normally towards each other; an arm 28 on the rock shaft 6; a pivoted arm 29 on the rock shaft arm 28 carrying wedge or cam-shaped members 30—30 to act upon the arms of the

brake mechanism timed to act simultaneously with the release mechanism; a downwardly-depend ing rock shaft arm 7 on the rock shaft 6; a spring 8 for throwing the same normally forward; a push rod 9 with a button 10 at its forward end for actuating the said tabulator mechanism; and a stop means for limiting its movement, all coacting substantially as described and for the purpose specified.

4. In a tabulator mechanism for typewriters, the combination of the main frame 1 of the typewriter; a carriage 2 thereon; an escapement mechanism for the carriage; an adjustable stop means on the said carriage; a rock shaft arranged transversely through the main frame; a movable stop means actuated from said rock shaft; a release means for the escapement; an arm on the rock shaft with connections from the release means thereto; a spring drum 39 for actuating the carriage; a brake mechanism for engaging the opposite faces of the said spring drum, consisting of a pair of arms or members 32—33 supported on a fixed shaft 31 by the said shaft extended through slotted holes in said arms; adjustable spring devices for holding the said arms normally towards each other; an arm 28 on the rock shaft 6; a pivoted arm 29 on the rock shaft arm 28 carrying wedge or cam-shaped members 30—30 to act upon the arms of the brake mechanism timed to act simultaneously with the release mechanism; a downwardly-depend ing rock shaft arm 7 on the rock shaft 6; a spring for throwing the same normally forward; a push rod with a button 10 at its forward end for actuating the said tabulator mechanism; and a stop means for limiting its movement, all coacting substantially as described and for the purpose specified.

5. In a tabulator mechanism for typewriters, the combination of the main frame 1 of the typewriter; a carriage 2 thereon; an escapement mechanism for the carriage; an adjustable stop means; a release means to act upon the escapement; a brake means for controlling the movement of the carriage; a rock shaft 6 arranged transversely through

the main frame; connections from said rock shaft to the said stop, release and brake mechanism; a downwardly-depend ing rock shaft arm 7 on the rock shaft 6; a spring 8 for throwing the same normally forward; a push rod 9 with a button 10 at its forward end for actuating the said tabulator mechanism; a stop collar 9' on the rod 9 for limiting its movement; and a notched lock plate 12 for engaging the stop collar 9' to secure the mechanism against accidental operation, all coacting substantially as described and for the purpose specified.

6. In a tabulator for typewriters, the combination of a stop mechanism consisting of the stop bar 21, the rock shaft 6, the arm 20 on said rock shaft notched on its under side at 22, a pivot pin on the lower end of said stop bar resting in said notch, and a spring on the under side of the said rock shaft arm for holding the said stop bar yielding upward, coacting for the purpose specified.

7. In a tabulator for typewriters, a stop mechanism consisting of a series of stops on the carriage; a stop bar 21, a rock shaft 6, an arm 20 on said rock shaft for moving said stop bar transversely into the path of the said stops on the carriage, and a yielding connection between said rock shaft arm and the said stop bar, coacting for the purpose specified.

8. In a tabulator for typewriters, a brake mechanism consisting of the spring drum 39 for driving the carriage, the oppositely-arranged arms or brake members 32-33 loosely pivoted together by slotted apertures 32"-33" in ears 32'-33' thereon, a shaft 31 in said apertures, an adjustable spring mechanism for holding the said arm yielding together, whereby the arms will act on the pivot as a fulcrum for opening the said arms, a pivot plate 29 with a cam part 30-30 to be forced between the ends of said brake arms for actuating the same, and a rock shaft with an arm 28 carrying the pivot plate 29, coacting for the purpose specified.

9. In a tabulator for typewriters, a brake mechanism consisting of a spring drum 39 for driving the carriage, the oppositely-arranged arms or brake members 32 and 33 loosely pivoted together by slotted apertures 32"-33" in ears 32'-33' thereon, a shaft 31 in said apertures, a spring mechanism for holding the said arms yielding together, whereby the said arms will act on the pivot as a fulcrum for opening the said arms, a pivot plate 29 with the cam part

30-30 to be forced between the ends of 60 said brake arms for actuating the same, and a rock shaft with an arm 28 carrying the pivot plate 29, coacting for the purpose specified.

10. In a tabulator for typewriters, a brake 65 mechanism consisting of a spring drum 39 for driving the carriage, the oppositely-arranged arms or brake members 32 and 33 loosely pivoted together by slotted apertures 32"-33" in ears 32'-33' thereon, a 70 shaft 31 in said apertures, a spring mechanism for holding the said arms yielding together, whereby the said arms will act on the pivot as a fulcrum for opening the said arms, and a pivot plate 29 with the cam part 75 30-30 to be forced between the ends of said brake arms for actuating the same, coacting for the purpose specified.

11. In a tabulator for typewriters, a brake mechanism consisting of a spring drum for 80 driving the carriage, the oppositely-arranged arms or brake members pivoted on a suitable support and arranged to embrace the opposite faces of said drum, a spring for holding said members yielding open, and a pivot- 85 means suitably connected for operating the said members to cause them to yielding grasp the opposite faces of the drum, all coacting for the purpose specified.

12. In a tabulator for typewriters, a brake 90 mechanism consisting of a spring drum for driving the carriage, the oppositely-arranged arms or brake members on a suitable support and arranged to embrace the said drum, a spring for holding said members 95 yielding open, and a cam means suitably connected for operating the said members to cause them to yielding grasp the opposite faces of the drum, all coacting for the purpose specified.

13. In a tabulator for typewriters, the combination of a brake mechanism consisting of oppositely-arranged arms loosely pivoted on a suitable support; a spring for holding the said brake members yielding open and in tension on said loose pivot; and a pivotal cam means for actuating the said members to cause them to move towards each other, the said members being arranged to grasp a movable part of the carriage mechanism, for the purpose specified.

In witness whereof, I have hereunto set my hand and seal in the presence of two witnesses.
